(57) **CLAIM**

The ornamental design for a magnetic device mounting head, as shown and described.

DESCRIPTION

FIG. 1 is a front perspective view showing a magnetic device mounting head;

FIG. 2 is a rear perspective view thereof;

FIG. 3 is a top plan view thereof;

FIG. 4 is a front elevation view thereof;

FIG. 5 is a right side elevation view thereof;

FIG. 6 is a left side elevation view thereof;

FIG. 7 is a rear elevation view thereof; and,

FIG. 8 is a bottom plan view thereof.

The broken lines illustrate portions of the magnetic device mounting head that form no part of the claimed design.

1 Claim, 3 Drawing Sheets
